United States Patent

Des. 240,740

Patented July 27, 1976

240,740

CIGARETTE PAPER

Kenji Fukushima, 1-14-8 Toneri-cho,
Adachi-ku, Tokyo, Japan

Filed Apr. 8, 1974, Ser. No. 458,594

Term of patent 14 years

Int. Cl. D27—01

U.S. Cl. D27—1

Fig -1

Fig -2

FIG. 1 is a front elevational view of a cigarette paper showing my new design; and

FIG. 2 is a rear elevational view of the paper shown in FIG. 1.

Although a side view has not been included it is to be understood that the cigarette paper of the present design is of normal thickness for such paper.

I claim:

The ornamental design for a cigarette paper, as shown and described.
